FRANK CARTER AND EVERSHED CARTER, OF STAMFORD, ENGLAND.

FUEL-INJECTION MECHANISM FOR INTERNAL-COMBUSTION ENGINES.

Application filed October 11, 1924, Serial No. 743,122, and in Great Britain October 31, 1923.

This invention relates to spring injector mechanisms for internal combustion engines of that type in which fuel is received in a receiving chamber and is injected therefrom into the cylinder (without admixture of spraying air) when the piston is at or about the end of its compression stroke by means of a plunger actuated by a coiled spring or other compressible member strong enough to inject the oil into the cylinder against the pressure of the compressed charge, the spring member being compressed at each cycle.

In this connection, we observe that other types of injector mechanism exist in which the injection of the fuel is effected by pneumatic means such as compressed air derived from a storage cylinder or compressor pump or alternatively derived from the compressed charge in the engine cylinder under the compression stroke of the piston. Such pneumatic devices have rendered it possible to control the time of injection of the fuel by means of what may be described as a trigger mechanism according to which an exceedingly small movement of a member operatively connected to the crank shaft suddenly releases the full force of the compressed injector-operating fluid so that the moment of commencement of injection remains practically constant under all conditions of load. The moment of cut-off of the injection opening in such devices is rendered variable according to the amount of fuel injected at each charge by means of a pressure-opened self-closing valve controlled by a spring adapted to close the valve against explosion pressure but to allow the valve to yield against the pressure of the injection fluid.

This arrangement is very advantageous in connection with internal combustion engines designed to insure combustion of fuel at constant pressure, and minimizes dribble of fuel from the injector nozzle both before and after the designed period of ignition. It suffers however, from the disadvantage that either a compressor pump or equivalent machine for the constant renewal of pneumatic fluid requires to be installed with the engine, or alternatively when the said pressure is derived from the engine cylinder, trouble is experienced in connection with the escape of tarry fuel residues into the injector mechanism; and the present invention has for its object to provide an equiva-

lent trigger action with a constant commencement and variable termination of the period of opening of the injector passage in connection with spring injector mechanism wherein a metallic spring is repeatedly compressed and allowed to expand, or if an air or like fluid spring is used the supply of fluid is repeatedly compressed and allowed to expand without necessitating means whereby the supply is constantly renewed.

We may here observe that it has also been proposed to provide a fuel receiving chamber having a movable injector plunger reciprocable therein and moved back at each cycle against the pressure of a coiled spring by a cam operating against a cam roll. With this device, the plunger is moved back its full stroke at each cycle so that there is a certain amount of lost motion when a small charge is being injected by the plunger, which causes dribble at or just prior to the commencement of injection and delay to the actual commencement of injection; and further, especially at slow speeds such as when starting, the plunger is held up by the nose of the cam which requires to move clear of the cam roll before the plunger can perform its injection stroke.

We have found that these minute interferences with the theoretical timing of the device are of considerable importance in practical working, and it is an object of the present invention to eradicate them, it being an important feature of invention to use a spring-controlled injector plunger moved back at each cycle the minimum distance required to accommodate the variable charge of fuel received in the receiving chamber in combination with a pressure-opened self-closing valve of which the time of opening is fixable in the cycle, the plunger being immediately free to perform its injection stroke as soon as the self-closing valve is allowed to open against the resistance of the fuel and of the self-closing valve, there being no mechanically-operated member fouling or encroaching upon its operative travel at any time.

Referring now to the drawings:—

Fig. 1 illustrates the first modification in end view with parts in section.

Fig. 2 being a plan thereof also with parts in section.

Fig. 3 illustrates the second modification in part sectional elevation.

Fig. 4 being a sectional plan of part of the

combustion chamber and injector valve corresponding to Fig. 3.

Referring now to Figs. 1 and 2, *a* is a combustion chamber to which is secured an injector block *b*. *c*, Fig. 2, is an injector valve pressed on its seat *c* by a spiral spring *c*² acting through the stud *c*³.

d, Fig. 1, is an oil chamber to which fuel is delivered by a governed pump (indicated diagrammatically in dotted lines in Fig. 1) through a non-return valve *d*¹. This chamber *d* communicates through a port *d*² with an annular chamber *c*⁴ around the valve *c*.

*d*³ is an injector plunger arranged at right angles to the valve *c* and acted upon at its outer end by a spring plunger *e*, surrounded by the spring *e*¹ which is normally held in partial compression by the nut *e*² bearing against a spring abutment collar *e*³.

20 *e*⁴ is a cap screwed upon the collar *e*³ and adapted to be pressed inwards by a roller *f*¹ on the lever *f*, pivoted at *f*². The collar *e*³ and cap *e*⁴ form a housing for the nut *e*² of the plunger *e* which overlaps the housing, 25 and it will be seen that the two parts are incapable of separation when assembled and are continuously urged apart by the spring *e*¹ which is normally under compression.

The lever *f* is actuated by the crank *g*¹ 30 on the camshaft *g* through a rod *g*².

h is a lug on the lever *f* adapted to engage the end of an adjustable link *h*¹ at the end of the inward travel of the lever *f* and thereby to take the pressure of a spring *h*² off 35 the stud *c*³, Fig. 2, on which it acts through the intermediary of a bell-crank lever *h*³.

The operation of the apparatus is as follows:—At any suitable point in the cycle, fuel in measured quantity according to the 40 speed of the engine is delivered by the governed pump to the chamber *d* thereby forcing the plungers *d*³ and *e* outwardly. The collar *e*³ in the cap *e*⁴ which provides a floating abutment for the injector spring *e*¹ moves 45 outwardly with the plungers as the spring *e*⁵ is a very weak spring by comparison with the spring *e*¹. At this time the lever *f* is moving towards the outward end of its travel and the nut *e*² is up against the collar *e*³.

50 During the return movement of the lever, the cap *e*⁴ is forced inwardly compressing the spring *e*¹ against the resistance of the oil which is held from escaping into the combustion chamber by the springs *h*² and *c*² acting on the valve *c*.

When near the end of its stroke, the lever *f* rocks the bell-crank lever *h*³ slightly thus taking the force of the spring *h*² off the valve and allowing it to open under pressure of 60 the oil in the chamber *c*⁴ and passage *d*² against the pressure of the spring *c*², whereupon the plunger spring *e*¹ forces the oil through the valve into the combustion chamber. The drawing shows the lug *h* just 65 striking the end of the adjustable link *h*¹.

and the spring *e*¹ compressed ready to deliver the fuel as soon as the lever *f*, by a slight movement to the left (Fig. 1), takes up the pressure of the spring *h*².

From the above description, it will be 70 seen that the injection always starts at the same point in the cycle, and finishes at a point governed by the quantity of oil to be injected.

i is a screw valve for the release of imprisoned air in order to render the ports and chamber solid with oil.

Referring now to Figs. 3 and 4, *a* is a fuel-receiving chamber in communication with a cylinder *c* in which an injector plunger *d* is movable outwardly by a spring *e* to draw in fuel through the non-return valve *b*. The outer end of the injector plunger is in contact with the inner part *f* of a spring plunger the outer part *g* of which carries a bush *h* in which the stem *i* of the part *f* can slide. A spring *j* considerably stronger than the spring *e* is interposed between the inner and outer parts *f*, *g* of the spring plunger, the separation of these parts by the spring *j* being limited by a head on the stem *i*, arranged so as to keep the spring under an initial compression.

A lever *k* pivoted at *l* is oscillated by a cam *m* rotating synchronously with the crank shaft of the engine, the said lever being held against the cam by the spring *e* pressing the injector plunger and the spring plunger outwardly together as fuel is drawn into the receiving chamber *a*.

The shaft carrying the cam *m* is geared to a governor shaft *n* carrying weighted arms *o* arranged when they move outwardly to adjust the position of a lever *p* against the thrust of a spring *q*. Movement of the lever *p* raises or lowers a suspended wedge-shaped block *r* slidable against a fixed abutment *s*, and the position of the block *r* by obstructing the movement of a projection *t* on the lever *k* determines the maximum amount of outward movement of the injector plunger and spring plunger moving together. The quantity of fuel admitted through the valve *b* at each outward movement of the injector plunger is thus governed by the speed of the engine crank shaft.

The chamber *a* communicates with a conduit *u* leading to the engine combustion chamber, the flow of fuel through this conduit being controlled by a valve *v* held closed by the pressure of the spring *a*¹. When the lever *k* is moved by the cam *m*, the outer part *g* of the spring plunger is moved inwardly compressing the spring *j* against pressure of the oil in the chamber *a*. In the last stage of the inward movement of the lever *k* and at a predetermined point of the cycle, a stud on said lever strikes against the stem of the valve *v* and opens this valve. Fuel is then injected into the

conduit *u* by the expansion of the spring *j*, and is admitted thence to the combustion chamber *w* through a valve *x* opened by the pressure of the fuel, against that of a

5 spring *y*.

The operation of the parts hereinabove re-

ferred to is as follows:—As the cam bowl moves from the high to the low portion of

the cam it permits the spring *e* to move the

10 spring plunger *f*, *g*, outwards as a whole,

the parts being in the expanded position

since the pressure of the spring *e* is insuffi-

cient to compress the spring *j*. This move-

15 ment causes fuel to be drawn into the cham-

ber *a* through the valve *b*, in quantities regu-

lated by the position of the wedge block *r*.

On the return stroke of the lever *k* the

spring *j* is compressed against the resistance

of the fuel imprisoned in the chamber *a*

20 until the valve *v* is opened by the lever *k*

thus permitting the spring *j* to expand and

force the fuel through the conduit *u* and

25 valve *x* into the combustion chamber.

This injection continues until the head

25 of the stem *i* comes up against the bush *h*,

thus stopping the expansion of the spring

j, and taking the pressure off the fuel, on

the removal of which pressure the valve *x*

30 is closed by the spring *y*.

In both forms, the time of commencement

of injection into the combustion chamber

will be constant for all speeds of the engine,

whilst the time of completion of injection

varies with the quantity injected in order

35 that the combustion shall be at or approxi-

mately at constant pressure.

We claim:—

1. In an internal combustion engine of the kind in which liquid fuel is injected into a charge of compressed air in the cylinder, an accumulator chamber, an injector plunger slidable therein, a spring member engaging therewith, means to compress said spring member at each cycle, means whereby a variable quantity of fuel is supplied to said chamber at each cycle, means whereby said injector plunger moves back at each cycle the minimum distance required to accommodate said variable quantity of fuel, a nozzle, a passage from said chamber to said nozzle, a pressure opened self-closing valve controlling said passage, and means to fix the time of opening of said valve, said plunger being thereupon free to perform its operative stroke against the resistance of the fuel and of said self-closing valve under the expansion of said spring member.

2. In an internal combustion engine of the kind in which liquor fuel is injected into a charge of compressed air in the cylinder, an accumulator chamber, an injector plunger slidable therein, a spring member engaging therewith, means to compress said spring member at each cycle, means whereby a variable quantity of fuel is supplied to said

chamber at each cycle before said spring member is compressed, means whereby said injector plunger moves back at each cycle the minimum distance required to accommodate said variable quantity of fuel, a nozzle, a passage from said chamber to said nozzle, a pressure opened self-closing valve controlling said passage, and means to fix the time of opening of said valve, said plunger being thereupon free to perform its operative stroke against the resistance of the fuel and of said self-closing valve under the expansion of said spring member.

3. In an internal combination engine of the kind in which liquid fuel is injected into a charge of compressed air in the cylinder, an accumulator chamber, an injector plunger slidable therein, a spring member engaging therewith, means to compress said spring member at each cycle, means whereby a variable quantity of fuel is supplied to said chamber at each cycle before said spring member is compressed, means whereby said injector plunger moves back at each cycle the minimum distance required to accommodate said variable quantity of fuel, a nozzle, a passage from said chamber to said nozzle, a pressure opened self-closing valve controlling said passage, and means to fix the time of opening of said valve, said plunger being thereupon free to perform its operative stroke against the resistance of the fuel and of said self-closing valve under the expansion of said spring member.

4. In an internal combustion engine of the kind in which liquid fuel is injected into a charge of compressed air in the cylinder, an accumulator chamber, an injector plunger slidable therein, a spring member engaging therewith, means to compress said spring member at each cycle, means whereby a variable quantity of fuel is supplied to said chamber at each cycle, means whereby said injector plunger moves back at each cycle the minimum distance required to accommodate said variable quantity of fuel, a nozzle, a passage from said chamber to said nozzle, a pressure opened self-closing valve controlling said passage, a supplementary load adapted to be placed on said valve, engine-operated means to first compress said spring member at each cycle after the fuel has been received in said chamber and thereafter to take said load off said pressure opened valve whereupon said plunger is free to perform its operative stroke against the resistance of the fuel and of said pressure-opened valve under the expansion of said spring member.

5. In an internal combustion engine of the kind in which liquid fuel is injected into a charge of compressed air in the cylinder, an accumulator chamber, an injector plunger

slidable therein, a spring member engaging therewith, means to compress said spring member at each cycle, means whereby a variable quantity of fuel is supplied to said chamber at each cycle before said spring member is compressed, means whereby said injector plunger moves back at each cycle the minimum distance required to accommodate said variable quantity of fuel, a nozzle, 10 a passage from said chamber to said nozzle, a pressure opened self-closing valve controlling said passage, and means to fix the time of opening of said valve, said plunger being

thereupon free to perform its operative stroke against the resistance of the fuel and 15 of said self-closing valve under the expansion of said spring member, a floating abutment to said spring member slidably connected to said injector plunger but incapable of separation therefrom, said abutment being free to move independently of the movement of the crank shaft.

In testimony whereof we affix our signatures.
